UNITED STATES PATENT OFFICE.

ARTHUR RALPH TREAT, OF GYPSUM, KANSAS.

WOOD-SPLITTING MACHINE.

1,425,298.

Specification of Letters Patent. Patented Aug. 8, 1922.

Application filed July 13, 1921. Serial No. 484,463.

To all whom it may concern:

Be it known that I, ARTHUR R. TREAT, a citizen of the United States, and a resident of Gypsum, in the county of Saline and State of Kansas, have invented certain new and useful Improvements in Wood-Splitting Machines, of which the following is a specification.

This invention relates to wood splitting machines and has for its object to provide novel means whereby the ax or splitting member may be elevated and subsequently released so as to drop by force of gravity on to the wood and thereby split the same.

Further, the invention aims to provide novel means whereby the blow struck by the ax is cushioned so that the machine will not be unnecessarily strained.

A further object is to provide a machine of the class described which is efficient in use, durable and cheap to manufacture.

Other objects and advantages of the invention will be apparent during the course of the following description.

In the accompanying drawing:

Figure 1 is a side elevation of the improved wood splitting machine.

Figure 2 is a plan view of the same.

Figure 3 is a detail sectional view through a power transmitting wheel.

In the drawings the numeral 5 designates a base upon which a source of power 6 in the nature of an internal combustion engine is mounted, the said engine having connection with a belt 7 trained about a power transmitting wheel 8. As illustrated in Figure 2 the power transmitting wheel 8 is mounted upon a cross shaft 9 rotatably carried by bearings 10 supported by brackets 11.

A power wheel 12 is carried by a shaft 13 mounted in bearings 14 supported by the brackets or standards 11 and the said wheel 12 is provided with a laterally projecting crank pin 15 to which a flexible element 16 is connected. The flexible element 16 is trained about a pulley 17 rotatably connected to the upper end of a U-shaped guide frame generally designated by the numeral 18 and having spaced parallel upstanding sides 19. One end of the cable is connected to the head 20 of an ax 21 and when the cable is released by means to be described the head and the ax drop by force of gravity and thereby split the wood mounted upon a chopping block 24. With refer-

ence to Figure 1 it will be observed that the ends of the head 20 are provided with grooved bearing members 25 which receive the inner sides of the upstanding portions 19 of the guide frame 18.

The action of the ax is cushioned by means of a pair of stout coil springs 27 arranged at the lower portions of the sides 19 immediately below inwardly extending stop elements 28 arranged in the path of travel of the head 20. When the head 20 moves downwardly it engages the inwardly extending stop elements 28 so that the downward movement of the ax is limited. However, by reason of the coil springs 27 the ax 20 moves downwardly to a slight extent after the engagement of the head with the stop elements and thereby splits the wood.

The power transmitting wheel 12 is provided with a semi-circular series of laterally projecting roller pins 30 with which the teeth of a sprocket wheel 31 are adapted to be engaged whereby the sprocket wheel is operatively connected to the power wheel 12.

In operation, the sprocket wheel 31 is rotated in one direction and by reason of its engagement with the roller pins 30 causes the wheel 12 to be rotated for elevating the ax. When one end of the series of laterally projecting pins passes the sprocket wheel the driving connection between the wheel 31 and the wheel 12 is broken whereupon the ax 21 drops and splits the wood. When the ax reaches the limit of its downward movement the series of pins are again engaged with the sprocket wheel so that the driving connection between the sprocket wheel 31 and the wheel 12 is renewed.

The laterally projecting pins 30 at one end of the series of pins are yieldably held in position by means of a coil spring 36 attached to the rim of the wheel 12 by means of a fastening device 37. As illustrated in Figure 3 the yieldably mounted pins are provided with shanks 38 slidable through slots 39 in the rim of the wheel. This construction permits the first pins 30 to be moved outwardly to a limited degree so that the sprocket wheel will be engaged with the pins without unnecessary strain.

With reference to the foregoing description taken in connection with the accompanying drawings it will be apparent that the wood placed upon the block 24 is split to the desired size by the action of the ax 21.

The operation of the ax may be stopped at any time by bringing a releasing lever 40 into engagement with one of the pins 30. The releasing lever 40 is operated by means 5 of a link 41 having connection with one branch of a bell crank foot pedal 42 arranged adjacent the block 24 so that the same may be readily operated.

As clearly illustrated in Figure 1 the lever 10 40 is engaged with one of the pins 30 after the pins 30 have moved out of engagement with the teeth of the sprocket wheel. The operator can conveniently engage the lever 15 with the pins at the proper moment by waiting until the pins 30 have passed out of engagement with the sprocket wheel.

A simple and equally effective method of engaging the lever 40 with one of the pins 30 is by manually rotating the wheel 12 20 until the desired point is reached and then depressing the pedal 42 so that the lever 40 will be elevated and engaged with one of the pins.

When it is desired to stop the operation 25 of the machine without stopping the motor the foot pedal 42 is operated for bringing the

lever 40 into locking engagement with the pins 30.

I claim:

1. A machine comprising a power gear, a 30 mutilated gear having an arcuate series of teeth adapted for engagement with said power gear, a tool having a flexible element connected to said mutilated gear and forming a means whereby to elevate the tool, the 35 line of pull on said flexible element being movable across the axis of said mutilated gear whereby the initial downward movement of said tool moves the arcuate series of teeth into engagement with said power gear, 40 the teeth at one end of said series of teeth being yieldably supported.

2. A woodchopping machine comprising a rotatable member having an arcuate series of laterally projecting pins, a power wheel 45 adapted for engaging said pins whereby to rotate said wheel, the pin at one end of said series of pins being yieldably supported, and a reciprocating wood chopping tool associated with and operated by said rotatable 50 member.

ARTHUR RALPH TREAT.
